CLAIM

The ornamental design for a fish shaped slide lock, as shown and described.

DESCRIPTION

FIG. 1 is a perspective view of the fish shaped slide lock of the present design shown in the environmental use.

FIG. 2 is an enlarged perspective view of the fish shaped slide lock encircled in FIG. 1.

FIG. 3 is a front elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a rear elevation view thereof.

The dashed lines in FIG. 1 illustrate environment and form no part of the claimed design.

The dashed lines on the front face of the fish shaped slide in FIGS. 2 and 3 form no part of the claimed design.

The broken lines in FIGS. 2, 4, 5 and 8 indicate the boundary and form no part of the claimed design.
